UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BINDER.

Application filed September 18, 1921. Serial No. 500,364.

To all whom it may concern:

Be it known that I, CLARENCE D. TRUSSELL, a citizen of the United States of America, residing in Poughkeepsie, in the county of 5 Dutchess and State of New York, have invented certain new and useful Improvements in Loose-Leaf Binders, of which the following is a specification.

This invention relates to so-called ring 10 binders for binding together, usually in book form, perforated leaves or sheets, the perforations being engaged by prongs or hooks formed to make mating engagement and when united constituting in appearance 15 a ring of more or less approximation to circular form, the hooks being mounted on plates which have rocking engagement at their abutting edges, and are spring actuated with a toggle action so that the spring 20 pressure is neutralized in a position of the hooks between closed and fully open, and the spring pressure acts with its maximum advantage when the hooks are closed to hold them closed, and when they are open to hold 25 them open. For brevity I will refer to this type of binder as the spring-pressed toggle type. In such binders the hook plates are in alignment in the neutral position, so that the spring pressure is ineffective, and in 30 moving to either side of this neutral position the plates buckle with a toggle action, so that the spring pressure becomes effective in proportion as the plates pass out of alignment. Commonly the spring is applied as a 35 curved back plate having its opposite edges turned inwardly to form flanges which embrace the outer edges of the plates; but the spring may be variously applied in binders of this type.

40 The invention provides improvements in the construction of the hook carrying plates whereby their abutting edges are held in alignment and their movement to open the hooks is limited; in the mode of attaching 45 the hooks to the plates; in an opener for throwing the hooks open; and in end caps for closing the opposite ends of the metallic members of the binder.

The preferable construction is shown in 50 the accompanying drawings, wherein—

Figure 1 is a plan of the binder (the usual book cover being omitted) with the hooks closed.

Fig. 2 is a similar view, the usual cover 55 plate being removed. Fig. 2^a is an enlarged

fragment of one of the hook plates shown in Fig. 2.

Fig. 3 is a view similar to Fig. 1, but showing the binder in use with the sheets or leaves in position.

Figs. 4 and 5 are transverse sections on a larger scale, taken in the plane of the line 4—4 in Fig. 2.

Fig. 6 is a fragmentary longitudinal mid-section of one end of the binder.

Fig. 7 is a transverse section on the line 7—7 in Fig. 6.

Fig. 8 is a side elevation of an end cap.

Fig. 9 is a plan of the end shown in Fig. 6, partly broken away in horizontal section.

Fig. 10 is a fragmentary longitudinal section in the plane of the line 10—10 in Fig. 4.

In the particular construction shown, the improved binder has hooks or half rings A A carried on plates B B, having rocking edge contact at their inner or abutting edges and embraced at their outer edges by the in-turned flanges on a spring back plate C of the usual bowed type. The hook plates are covered by a cover plate D, which has 75 hooked edges embracing the edges of the spring plate C, as is usual. This cover plate is usually made of very thin metal, and commonly has little or no spring function, but it may be made resilient and caused to co-act 80 with and reinforce and strengthen the spring action of the spring plate C.

The inner edges of the plates B B are 85 squeezed or swaged at intervals to form tongues a a, which are of a thickness approximately half that of the plates, the swaging operation being performed by dies in such manner as to force the displaced metal outwardly beyond the edge of the plate, in the manner best shown in Fig. 2^a and in the sections Figs. 4 and 5. Opposite each projecting tongue the other or mating plate is reduced in thickness by swaging, so as to form a recess b into which the tongue may enter. The tongues project on the lower half of each plate, and the recesses they enter are on the lower half of the mating plate in each instance. Each tongue is bent downward to an angle corresponding with the upward angle formed by the plates when in the open position of the hooks, as shown in Fig. 5; consequently, in the closed position of the hooks these tongues project downwardly, as shown in Fig. 4. This downward movement of the hook plates is 100

105 110

limited by the abutting of the ends of the hooks; the upward movement shown in Fig. 5 is limited by the abutting of the tongues against the undersides of the recesses, as shown in Fig. 5. This tongue abutment is adequate for limiting this opening movement; but it is desirable also, when the cover plate D is used, to have this plate fit so closely that at extreme opening movement the inner edges of the plates will touch or nearly touch the underside of the cover plate, as shown in Fig. 5, thus affording a double security against the hooks being forced open too far. The cover plate D may, however, be omitted, as it forms no necessary part of the present invention. The construction thus described affords a very simple, cheap, effective and easily assembled means for accomplishing a rocking joint between the abutting edges of the hook carrying plates. The tongues are alternated at intervals so that they hold the inner edges of the plates in alignment and preserve their rocking contact. The longitudinal positions of the plates, such as to keep the hooks in mating register, is insured by forming the tongues in pairs close together so that they have a lateral abutment, those of one pair in one direction and those of another pair in the contrary direction, whereby it is impossible for either plate to be longitudinally displaced relatively to the other.

E is an opener for forcing open the hooks by imparting the opening movement to the hook plates. The construction of this opener is in some respects an improvement on that set forth in my application filed February 24, 1920, Serial No. 360,712. As in that prior construction, the opener consists of a lever consisting of metal plate set in a plane extending longitudinally of the plates B, C and D, being perpendicular to the hook plates when in their aligned mid-position, and thus occupying a longitudinal medial plane and moving in this same plane with a rocking movement. The opener constitutes a lever which reacts against the spring plate C and has a portion which engages beneath the hook plates. Its operating arm extends up through a slot f in the top plate and is formed with a thumb piece or button g, which formerly was round but now is fan-shaped so as to better accord with and enter between the curved corners of the loose leaves or sheets G G, as shown in Fig. 3. Formerly the opener had a single rocking bearing at one point on the spring back plate, which had the disadvantage that its pressure was liable to displace or bulge outwardly the back plate at this point, since the back plate is commonly made of very thin spring metal, and as considerable pressure has to be applied to the opener to displace the hook plates upwardly, the reaction of this pressure being concentrated at

one point upon such thin metal was apt to deform it. This objection is obviated according to the present construction by providing a thickened or reinforced bearing for the opener to rock against, and by constructing the opener in rocker form so that its rocking bearing engagement continually shifts along the back plate as the opener is moved. The rocker bottom is lettered h, and the toe which lifts the hook plates is lettered i. The rocker bottom h has a continuous curve as shown, instead of having an angular bearing at one point against the back plate. This curve is so shaped as to have a cam action, its effect being to vary the ratio of leverage of the opener during its movement. When pressure is first applied the leverage is in the ratio of about 5 to 1, which diminishes during the movement until, when the hook plates are in alignment or dead center, the ratio of leverage diminishes to about 2½ or 3 to 1, as will be seen by comparing the full and dotted line positions shown in Fig. 6. The rocker bearing of the opener is against a reinforce plate j, which in action lies flat upon the spring back C. This reinforce plate is itself strengthened by having its sides turned up to form flanges k k. This reinforce thus forms a trough or channel which distributes the pressure exerted by the opener over a prolonged area of the spring back plate. The reinforce plate also serves to take up all looseness of the opener, and prevent rattling. To this end its side flanges k k yieldingly embrace the sides of the opener between them in such manner as to take up all lateral looseness, and the tongue j is made resilient to press the reinforce plate upward, so as to lift the opener and press its toe i against the under side of the hook plates, and its heel j' up against the under side of the top plate D or flange n. On pressing down on the thumb-piece g the opener is rocked, first forcing down the plate j against the back plate before prying up the hook plates. The reinforce plate j is held in position in any suitable way, so as to prevent its becoming displaced sideways, and so that it holds the opener in its proper mid-longitudinal plane. For thus locating the reinforce plate it is desirable to confine it between ears bent up from the spring back plate. These ears are shown in Fig. 7 at l, being pressed up laterally to engage the side flanges k when the reinforce is pushed down between them.

To make a neat finish at the ends of the binder metals, end plates or caps H H' are provided. These caps are of thin metal and comprise each an end plate m, a top portion n and a bottom portion p. The top plate D of the binder overlies the top portion n of the end plate shown in Fig. 6. To conceal the edge of the top plate D, the end plate

or cap is formed with a raised bead *q* extending across the top and abutting against the end of the top plate. The bottom plate or flange *p* underlies the spring back plate, 5 and preferably conforms closely thereto. The end caps may be held on in any suitable way. In the construction shown the spring back plate is formed with slots *r r* near its ends on opposite sides, these slots being at 10 its widest part just below its inturned flanges; and the top plate *n* of each cap is formed on opposite sides with bevelled or inclined ears *s* projecting outwardly and adapted, as the cap is pushed into place 15 from beyond the end of the metals, to enter yieldingly between the end flanges of the spring plate and force these flanges apart until the cap is fully seated, whereupon these ears enter the slots *r* partly by the 20 swinging inward of the flanges due to the resilience of the spring back plate, and partly by the resilient parts of the top plate *n* springing outwardly. The bevelled shape of the ears facilitates the assembling of 25 these parts; and when once assembled the abrupt sides of the ears form locking shoulders for effectually preventing the displacement of the caps. The caps can be removed only by means of a special tool to engage the 30 inturned flanges on the spring plate and press these flanges apart, or by forcing inwardly the ears *s*. It is desirable to form the top plate also with slots *r' r'* in its side flanges to receive the ears *s*, whereby these 35 ears also assist in holding the top plate in place.

It is desirable to form the reinforce plate *j* and the end cap *H* in one piece, as shown in Fig. 8. The end cap *H'* is shown as unprovided with any reinforce plate *j*, because it comes at the top of the book where an opener *E* is not required; but if an opener is used at each end, then the cap *H'* should be of the same construction as the cap *H*. 45 The advantage of forming these two parts *H, j* integrally is that each assists in locating and holding in place the other. Their connecting portion is a tongue *j'*, Figs. 6 and 9, which is devoid of side flanges *k*, and passes through an open slot *t* formed in the spring back plate, and which slot has to be long enough to admit the height of the side flanges *k*. In assembling the parts, the reinforce plate *j* is first introduced at nearly 50 right angles through the slot *t*, whereupon the cap is swung into position beyond the end of the spring plate, and is then thrust longitudinally into place, entering its top plate *n* between the flanges of the spring, as already explained. When the end cap is 55 locked in place by the engagement of the ears *s* with the slots *r*, the reinforce plate *j* becomes securely located so that its displacement is prevented.

60 The structure thus far described may be

fastened to the book back in any known or suitable manner. Commonly the fastening is accomplished by means of a curved binding plate between which and the spring back *C* the book back or part thereof (usually of fabric or leather) is clamped. Commonly the binding plate has prongs projecting from it which enter slots in the spring plate *C*, and are turned down to clamp the two plates together. With the 75 present construction, however, instead of providing as usual one such prong at each end, if end prongs are used it is necessary to provide two, and space them far enough apart to avoid interfering with the reinforce 80 plate *j*. The location of the prongs before turning down may be shown by dotted lines in Fig. 4, at *w w*. In Fig. 10 the fabric of the book back is shown at *I*, and the binding plate at *J*, its turned-in ears being shown 85 at *K*. Usually the fabric *I* is a binding strip, and the outer portion of the book back is exterior to the back plate *J* and extends somewhat beyond the end caps, being shown at *L* in Fig. 10. In order to avoid 90 the end of the binding plate *J* being exposed to view, which would be unsightly, the end caps *H* or *H'* are made to serve also the purpose of concealing these ends of the binding plate by flanging down the bottom plate or portion *p*, as shown at *u* in Figs. 6 and 8, this flange portion being extended downward far enough to cover the edge of the plate *J*.

In the particular construction shown, the 100 end hooks *A* are so close to the ends of the book or binder as to make it necessary to notch out the hook plates *B* at the end which is engaged by the opener *E*, this opener entering partly into such notches. This, 105 however, is unnecessary in constructions where the hooks do not approach so closely to the ends of the book.

The invention is not limited to all the 110 features of construction set forth, nor to the necessarily conjoint use of all the improvements described. The construction is subject to modification in many respects, as will be well understood by those skilled in the art. For example, the spring stress necessary to give the toggling action may be applied otherwise than through the use of a resilient back plate *C*, as is well understood.

115 While it is preferable for simplicity and cheapness that the hook carrying plates meet edge to edge, yet it is to be understood that in this art it is unnecessary that such edge contact be continuous, and it is also understood that the edge contact of the plates may be accomplished without their immediately touching each other, that is, by extending the base portions of the hooks to project slightly beyond the meeting edges of the plates, and making the rocking contact sur- 120 125 130

faces on the hooks whereby they hold the edges of the plates slightly separated. It is, however, one of the advantages of the present construction that it permits of a suitable rocking engagement by immediate contact between the edges of the plates.

I claim as my invention:

1. In a ring binder, hook-carrying plates having rocking edge contact, pressed resiliently edge to edge, the plates formed at their meeting edges with pairs of tongues and indentations, the indentations formed within the thickness of the plates on their under sides, and the tongues projecting from the under sides of the plates and entering the mating indentations, and alternated to hold the mating edges in alignment.

2. In a binder according to claim 1, the tongues abutting against the bottoms of the indentations to limit the opening movement of the hooks.

3. A loose leaf binder comprising hook plates having hooks, a back plate, and an opener having a rocking movement, reacting against the back plate, with an interposed reinforce plate to distribute its pressure against the back plate.

4. A binder according to claim 3, the reinforce plate having side flanges forming a channel in which the opener is guided.

5. A binder according to claim 3, the reinforce plate resilient and pressing against the opener to take up looseness.

6. A loose leaf binder according to claim 3, the binder having means providing lateral guides for the opener.

7. A loose leaf binder according to claim 3, the binder having means for laterally locating the reinforce plate and the latter having means for laterally guiding the opener.

8. A loose leaf binder comprising hook plates having hooks, a back plate and an opener, the latter comprising a flat metal plate the plane of which coincides with the longitudinal medial plane of the binder and movable in its own plane, and formed with a curved rocker bearing reacting against the back plate, and an interposed reinforce plate having an upward spring stress, the opener having toes at opposite ends, the one engaging beneath an overhanging portion, and the other engaging beneath the hook-plates, the upward stress of the reinforce plate pressing said toes into firm engagement with their overlying parts.

9. A ring binder comprising hook plates

having hooks, a back plate embracing said hook plates, and an end cap fastened to the back plate having an end portion, and a flange underlying and embracing the end portion of the back plate.

10. A ring binder comprising hook plates having hooks, a back plate embracing said hook plates, a top plate and an end cap, the latter comprising an end portion closing the space between the back plate and top plate, a top portion projecting beneath the top plate, and an intervening bead covering the end of the top plate.

11. A ring binder comprising hook plates having hooks, a back plate embracing said hook plates, a top plate and an end cap, the latter comprising an end portion closing the space between the back plate and top plate, a top portion projecting beneath the top plate, and an intervening bead covering the end of the top plate, and having also a flange extending under and conforming to the back plate.

12. A ring binder comprising hook plates having hooks, a back plate embracing said hook plates, and an end cap fastened to the back plate, having an end portion, and a top portion, the latter formed with laterally projecting ears and the back plate having within its flanges longitudinal slots engaged by said ears.

13. In a binder comprising hook plates and hooks, a back plate, an opener and an end cap, the latter formed with an extension projecting over the back plate to form a reinforce plate to receive the action of the opener and distribute it to the back plate.

14. In a binder comprising hooks and their carriers, a spring back plate and a binding plate for attaching the binder to a book back, an end cap for closing the open end of the back plate having a projecting rib located adjacent the end of the binding plate and concealing such end from view when the binder and book back are attached.

15. A ring binder comprising hook plates having hooks, a spring plate embracing the hook plates, and an end cap fastened to the spring plate, said end cap having a flange which underlies the spring plate, the flange having an end portion which passes above the lower portion of the spring plate.

In witness whereof, I have hereunto signed my name.

CLARENCE D. TRUSSELL.
